HALF-TUBULAR REINFORCED CONCRETE BEAM FOR USE IN BUILDING CONSTRUCTION

Paul William Abeles, London, England

Application May 1, 1941, Serial No. 391,358
In Great Britain March 13, 1940

3 Claims.

(Cl. 72—71)

This invention relates to improvements in half-tubular reinforced concrete beams for use in building construction, more particularly in floor and ceiling constructions, and provides new and advantageous forms of such beams which combine great strength and carrying capacity with a relatively small weight and a reduction in the amounts of reinforcement and concrete hitherto considered necessary.

According to the invention, a reinforced concrete beam for building constructions is formed by centrifugal moulding into half-tubular form with a substantially semi-cylindrical cavity, the external cross-section of the beam including one or more substantially straight lines, and transverse reinforcement members are fixed in predetermined positions within the beam by the engagement thereof with the longitudinal reinforcement members usually provided in such beams, such transverse members being subjected automatically to an initial tension due to the centrifugal method of casting the beam, thus increasing the carrying capacity of the beam due to the consequent reduction in the principal stresses thereof, and rendering it possible to employ reinforcement members of less weight than hitherto normally employed, and further to construct beams with walls of a thickness which is relatively small in comparison with the thickness of walls of previous beams. These reductions in the amounts of reinforcement and concrete afforded by the beams of the present invention are permissible in view of the added compactness and density which is known to result together with increased compressive and tensile strength in concrete structures formed by centrifugal moulding, combined with the results of the initial tension to which the transverse reinforcement members are automatically subjected by such centrifugal formation. The transverse members being engaged with the normal longitudinal reinforcement, forces are set up in the concrete opposite to the strains to which the beams are subjected in use, and the principal stresses to which the beam is subjected in use are considerably reduced.

According to the invention, such above described half-tubular beams are provided with shoulders and/or recesses in the external perimeters thereof, and if desired also in the cavities thereof, for purposes hereinafter more fully disclosed.

Such semi-tubular reinforced concrete beams may be used in the construction of floors laid with the cavity downwards, with or without the

addition in situ of a concrete or similar filling in the cavity, or may be laid with the cavity upwards the cavity thereafter being filled with concrete or similar filling, or provided with reinforcing concrete ribs. The said beams may also be employed as shuttering, in which case concrete is poured into the cavity in situ to form a girder, or they may advantageously be similarly employed as purlins, beams or the like.

10 The semi-tubular beams of centrifugally moulded reinforced concrete in accordance with the invention may be laid side by side in the construction of a floor or of a ceiling, or may be laid spaced apart, such spaces being bridged by slabs of concrete, brickwork or other suitable material.

By reason of the centrifugal method of manufacture of beams in accordance with this invention, and the consequent automatic application 20 to the transverse reinforcement members thereof of an initial tension, it is possible to employ beams with relatively thin walls without reducing the carrying capacity required of beams having walls of normal thickness, and without incurring the 25 risks of the development of cracks during transport or erection, or while in service.

Consequent upon the added strength of beams in accordance with the invention rendering possible the employment of beams with relatively thin walls and reduced weight, the further advantage is obtained that when a floor structure is constructed with the improved beams, a relatively very small average floor thickness can be obtained compared with normal concrete floor structures, with the advantages of saving in space 30 between floors and in the weight not only of the floor itself, but also of the load carried by the walls of the building or the supporting columns 35 or standards, and thus eventually in the load acting upon the foundations of the building. A saving in the costs of building is thus rendered possible, since the dimensions of the foundations and the supporting members can be reduced to 40 correspond with the reduced load which has to be maintained.

A further advantage of beams according to the invention when employed with the cavities thereof upwardly disposed, e. g. when used as shuttering, lies in that the increased resistance to the formation of cracks in the concrete under load makes it possible to reduce the number of, or entirely to dispense with, the usual intermediate props or supporting members between the walls 45 or main supports or columns.

The invention will now be described with reference to the accompanying drawing, in which

Figure 1 shows a section of a centrifugally moulded semi-tubular reinforced concrete beam in accordance with the invention.

Figure 2 is a section through a flooring made from beams in accordance with the invention showing several different methods of completion thereof.

Figure 3 is a section through an alternative form of flooring constructed with beams made in accordance with the invention, and

Figures 4 and 5 are sectional views showing the manner in which such concrete beams may be used as shuttering for girders,

Figures 6 and 7 are detail views showing means of providing anchorage for attaching slabs or plates to a beam, and

Figures 8 and 9 are sectional views showing the manner in which beams in accordance with the invention are used as purlins or flooring members.

As shown in the drawing, a flooring and ceiling or roofing may be formed by a number of reinforced concrete beams of substantially semi-cylindrical shape *a*, either laid side by side as shown in Figure 2, or spaced apart from each other as shown in Figure 3, with the cavities thereof downwardly disposed. Such beams are formed by centrifugal moulding in the known manner, with shoulders *c*, *f* and *g* thereon upon which may be secured ceiling or flooring slabs of concrete, brickwork or other suitable materials as hereinafter more fully described, and with lateral externally-projecting flanges or extensions *e*.

The said beams *a* may be provided with the following reinforcements: a main longitudinal tension reinforcement *b*¹, a secondary longitudinal reinforcement *b*², a transverse reinforcement *b*³, which may be in the form of a number of single links, and if desired with a further transverse reinforcement, which may comprise ties *b*⁴, which may be combined with the links *b*³. Alternatively the two transverse reinforcements may be combined in a continuous spiral, the parts of which extending across the cavity serving as the ties *b*⁴ and the parts thereof embedded in the concrete serving as the links *b*³. Where a transverse reinforcement or reinforcements is or are employed, they may be combined with the longitudinal reinforcements to form a rigid framework.

If desired, single tie members *b*⁴ may be employed without the links *b*³, such ties *b*⁴ serving to fix the positions of the longitudinal reinforcement members *b*¹ and also as anchorage members. The necessary fixing of the positions of the longitudinal reinforcements may alternatively be secured by the use of concrete rings (not shown), such rings being placed around the longitudinal members so as to determine accurately their distance from the exterior of the wall of the beam.

Longitudinal reinforcement members may project from the ends of the beam if desired, in the known manner, in order to provide means for connecting the beams to cross beams, girders, spreader beams, or other structural elements, and ensuring a rigid connection therewith.

When beams according to the invention are used in the construction of floorings, they may be laid side by side, as shown in Figure 2, and connected by cement or other mortar *m*, either in the form of spaced ribs or extending along the entire length of the adjacent beams. Alternatively, as also shown in Figure 2, the space be-

tween two beams may be filled with a light concrete or other filling *p*. The adjacent beams thus act together and a uniform deflection is ensured.

Where a wooden floor surface is desired, joists *n* for boards *o* may be supported on the cement filling *m*, which is here preferably provided in the form of spaced ribs; the remaining spaces between the beams being further provided with filling or not, as desired.

Where a plain concrete floor surface is required, this may be provided by the upper flat faces *a*¹ of the inverted beams together with either the upper flush surface of a filling such as *p*, or by the provision of concrete flooring slabs *q*, supported on the shoulders *g*.

The ceiling formed by the undersurface of such flooring constructions using beams in accordance with the invention may be left with the cavities of the beams visible, or a plane surface therefor may be provided, either of concrete, brickwork or other desired material. For this purpose, recesses having shoulders *c* are formed in the ends of the cavities of the beams, and slabs or plates *d* of concrete or brickwork are secured in position against such shoulders *c* in any convenient manner. For example, the ends of link members *b*³ may be arranged to project laterally from the external walls of the beam to provide anchorages upon which such slabs or plates *d* may be secured, or members such as flat metal strips or bars *l* (Figure 6), or wires, or cylindrical rods, or laths, or dowels countersunk longitudinally or transversely in the beams may be provided.

As shown in Figure 6, the flat metal strips *l* may be passed around the reinforcement members *b*¹ in the formation of the beam *a*, the ends thereof projecting from the inner face of the beam into its cavity, or as shown in Figure 7, where no shoulders *c* are provided in the beam, the strips *l* passing round the reinforcement members *b*¹ project downwardly and are then bent as shown to lie transversely across the cavity in the beam. In either case, such projecting parts *l* serve to form an anchorage to which may be secured slabs or plates *d* of concrete, cement or the like.

In constructing such a concrete-surfaced ceiling the concrete slabs or plates *d* may be secured in position by pressure moulding the same upon the shoulders *c* before the beams are placed in position, a core being inserted into the cavity of each beam (the cavity being uppermost during moulding) and removed after molding has been effected.

When a flooring is formed by beams according to the invention spaced apart one from the other, as shown in Figure 3, ceiling slabs *r* of concrete or other desired material are secured in position by the engagement of projecting parts thereof with the shoulders *f* previously referred to.

The beams of this invention are also readily applicable to roof constructions, and for use as shuttering, as shown, in Figures 4, 5, 8 and 9, in which cases they are laid with the cavities upwards or outwards. When so used as shuttering for the construction of girders in situ, the beams are advantageously formed with a greater height than width, whereas when employed for flooring constructions, the beams are preferably formed with the width thereof greater than the height, or with a somewhat flattened arch, thus reducing the total amount of concrete per square yard of floor normally necessary with beams of greater height.

As shown in Figures 4 and 5, the main longi-

tudinal reinforcement b^1 is situated in the top of the arch, and a secondary longitudinal reinforcement b^2 is advantageously provided to ensure an anchorage at or adjacent the ends of the semi-cylindrical walls, serving to provide an anchorage for transverse reinforcement members b^3 . Lateral extensions e of the beam serve as enlargements of the carrying space for the floor construction, which may comprise for example, beams V and floor boards or slabs W . The slabs W may be provided with reinforcement, parts s of which project into the space p^1 (Figure 4), which is preferably filled with a light concrete or other suitable filling material. The transverse reinforcement members b^3 of the beam a may similarly project into the space p^1 , as shown in Figure 4, and if desired, an additional longitudinal reinforcement t with transverse reinforcing members u may be provided in such cavity p^1 , as shown in Figure 5, so as to provide a suitable tensile reinforcement for a concrete girder formed by pouring concrete into the space p^1 , the beams a then acting as shuttering.

In flooring construction employing beams a with their cavities upwardly disposed, lateral shuttering above the beams may be provided by the use of suitably shaped slabs k of concrete or the like as shown in Figures 4 and 5. Ceiling slabs W^1 may be secured to the upper parts of the beams a below the flooring beams V as shown in Figure 5.

Figures 8 and 9 show beams a laid with their cavities upwardly disposed as for use in flooring or as purlins, roofing tiles, slabs or the like j being supported thereon when used as purlins, with concrete ribs h at intervals along the cavities thereof, such ribs h preferably being provided with reinforcement tie members. As shown in Figure 9, flooring slabs q are supported on shoulders c formed in lateral extensions e of the beams, the cavities of the beams being filled with concrete or other suitable filling, as shown. Instead of filling such cavities with concrete or the like, flooring or roofing slabs may be secured upon shoulders formed in the insides of the cavities, for example as shown in Figure 2 with reference to the ceiling slabs d .

According to a modification of the invention, unitary structural elements for use in building may be formed by beams as hereinabove described, having slabs or plates of concrete, cement or other suitable material secured positively to each beam and extending across the

cavity thereof. Such unitary structural elements have been found to be conveniently handled and transported and enable flooring and roofing constructions to be built in situ with a considerable saving of labour and inconvenience on the site.

Having now particularly described and ascertained the nature of my said invention and in what manner the same is to be performed, I declare that what I claim is:

1. A reinforced concrete beam for building construction, formed of concrete centrifugally moulded into half-tubular form comprising a plurality of longitudinally disposed reinforcement members within the concrete, and a plurality of transverse reinforcement members within the concrete, which transverse members engage said longitudinal members, and are under tension applied by the centrifugal motion that moulds the beam, which tension is maintained in said transverse members by the hardening of the concrete and wherein an additional reinforcement member of steel engages a pair of the longitudinal reinforcement members and extends across the cavity of the half-tubular beam.

2. In a concrete beam for building construction, made centrifugally into half-tubular form with longitudinally disposed reinforcement bars of steel, the improvement comprising a transverse reinforcement member of steel wire under tension which is impressed by the centrifugal force used in forming the beam and which tension is maintained by the hardening of the concrete, such wire member being in the form a loop which engages a plurality of longitudinal reinforcement members, a section of which loop is within the concrete of the beam and a section of which extends across the cavity thereof.

3. In a concrete beam for building construction, made centrifugally into half-tubular form with longitudinally disposed reinforcement bars of steel, the improvement comprising a transverse reinforcement member of steel wire under tension which is impressed by the centrifugal force used in forming the beam and which tension is maintained by the hardening of the concrete, such wire member being in the form a spiral, each loop of which engages a plurality of longitudinal reinforcement members, and a section of each loop being within the concrete of the beam and a section thereof being extended across the cavity of the beam.

PAUL WILLIAM ABELES.
